UNITED STATES PATENT OFFICE.

JULES B. BENEDICT, OF DENVER, COLORADO.

DESIGN FOR A COMBINATION BATH-ROOM FIXTURE.

52,763.

Specification for Design.

Patented Dec. 17, 1918.

Application filed March 30, 1917. Serial No. 158,755. Term of patent 3½ years.

To all whom it may concern:

Be it known that I, JULES B. BENEDICT, a citizen of the United States, residing in the city and county of Denver and State of Colorado, have invented a certain new, original, and Ornamental Design for a Combination Bath-Room Fixture, of which the following is a full, clear, and exact description, such as will enable others skilled in the art to which the design appertains to make and use the same.

In the drawing, Figure 1 is a side elevation view of the toilet fixture; Fig. 2 is an end view thereof; and Fig. 3 is the other end view thereof.

Having thus described my invention, I claim:—

The ornamental design for a combination bathroom fixture as shown.

JULES B. BENEDICT
